Wilhelm Simmchen

UNITED STATES PATENT OFFICE.

WILHELM SIMMCHEN, OF AUSSIG-KLEISCHE, CZECHOSLOVAKIA.

LOOM.

Application filed August 27, 1921. Serial No. 495,957.

(GRANTED UNDER THE PROVISIONS OF THE ACT OF MARCH 3, 1921, 41 STAT. L., 1313.)

To all whom it may concern:

Be it known that I, WILHELM SIMMCHEN, a citizen of the Czechoslovak Republic, residing at Aussig-Kleische, No. 142 F. A. 5 Virgnerstrake, Czechoslovakia, have invented certain new and useful Improvements in Looms, for which I have obtained the following foreign patents, England, Patent No. 161,155, dated May 26th, 1921; 10 Germany, Patent No. 355,848, granted April 27th, 1922; Czechoslovakia, Patent No. 7,695, dated February 7th, 1922; Switzerland, Patent No. 97,845, dated December 13th, 1922; Belgium, Patent No. 300, 15 541, granted December 31st, 1921; and Italy, application Serial No. 314/52, filed September 16th, 1921, and of which the following is a specification.

The usual method of mounting the crank 20 shaft in a loom, is to have the bearing for the end gudgeon fixed to the side wall or frame on the inside, the crank being thus on the inside of the said frame. A second bearing on the inner side of the crank is 25 provided mainly for steadyng purposes. With this arrangement an amount of space transversely of the loom equal to the full width of the crank is occupied by the crank inside of the loom. The crank is liable to 30 foul adjacent heddles, and when the bearings are worn, oil is liable to be projected onto the goods. Cranks mounted wholly outside the frame have also been used, but also in this case the crank is disposed 35 symmetrically to each side frame.

The arrangement of the crank eccentrically to the side frame restricts the speed of the running of the loom, and tends to distort the side frames, especially at the 40 moment of braking i. e. sudden stopping of the movement, this distortion depending upon the distance of the crank center from the center of the frame.

According to my invention the crank is 45 so mounted that its pin rotates in an aperture provided in the frame within which it is located, the center of the pin of each crank being substantially in the central plane of its respective frame, and the thrust 50 of the connecting rod being consequently in this plane, or near the same, since this rod is substantially located in that plane. With this arrangement a marked increase of steadiness and smoothness of running is ob-

tained, and there is no violent vibration if 55 the brake is suddenly applied, the thrust of the connecting rod against the crank being directly absorbed by the frame at and in the direction of its central vertical plane.

The invention is illustrated in the annexed drawings:—

Figure 1 is an elevation;

Figures 2 and 3 are sections on the line A—B of Figure 1, exemplified in two different forms of constructions; and

Figure 4 is a plan view, in section on the line C—D of Figure 1.

In the drawing *a* designates the side frame, and *b* a bracket fixed within a gap in the frame, and having two bearings for 70 the crank shaft, one at each side of the frame with the crank disposed between them, so that the crank pin center coincides with the central vertical plane of the side frame in which it is located, as may be seen 75 from Figure 2. *c* is the connecting rod and *d* the lay.

As shown in Figure 4 by dotted lines the new construction renders it possible to use the whole width of the loom to within 80 a small margin from the side frames.

The arrangement can be applied to existing looms, the lay and crank shaft being lengthened and strengthened as required. I have found for example, that with a certain type and width of loom, an increase of 85 18% in output can be obtained by this means, with the loom running at the same speed because of the greater widths of material which may be thus produced.

In applying the arrangement to an existing loom it may, of course, be necessary to cut or otherwise provide apertures in the side frames to receive the cranks. Separate brackets or the like, one for each bearing, 95 may be fixed to the frames, at each side thereof. With new looms one block for both bearings may be used as shown in Figure 2, or a block as shown in Figure 3, fastened to the wall with the bearing 100 screwed on from the inside.

What I claim is:—

1. A loom having the cranks for operating the lay located in its side frames, the center of each crank being in line with the 105 central plane of its respective frame to permit the frame to take up the entire reaction exerted by the crank and a bearing

disposed on each side of the crank and being attached to the frame, each frame having an aperture to permit free movement of the connecting rods attached to said 5 cranks.

2. A loom having the cranks for operating the lay located in its side frames, the center of each crank being in line with the central plane of its respective frame to permit the frame to take up the entire reaction exerted by the crank, and a bearing bracket for each crank having two bearings, 10

one located on each side of the crank, said bracket being attached to the side frame symmetrically to its central plane, each 15 frame having an aperture to permit free movement of the connecting rods attached to said cranks.

In testimony whereof I affix my signature in presence of two witnesses.

WILHELM SIMMCHEN.
